UNITED STATES PATENT OFFICE

JOHN P. CROASDALE, JR., OF BERWYN, AND JOHN ARTHUR ROBERTS, OF
PHILADELPHIA, PENNSYLVANIA

DESIGN FOR A PLANTING TOOL

Application filed October 5, 1932. Serial No. 45,233. Term of patent 7 years.

To all whom it may concern:

Be it known that we, JOHN P. CROASDALE, JR., and JOHN ARTHUR ROBERTS, both citizens of the United States and residents respectively of Berwyn, Chester County, State of Pennsylvania, and Philadelphia, county of Philadelphia, State of Pennsylvania, have jointly invented a new, original, and ornamental Design for a Planting Tool of which the following is a specification, reference be-

ing had to the accompanying drawing, forming part thereof.

Fig. 1 is a view in perspective.

Fig. 2 is an elevation.

Fig. 3 is a section on line 3—3 of Fig. 2.

We claim:—

The ornamental design for a planting tool as shown.

JOHN P. CROASDALE, JR.

JOHN ARTHUR ROBERTS.
